UNITED STATES PATENT OFFICE

HENRY LAMONT MURRAY, OF AUCKLAND, NEW ZEALAND, ASSIGNOR TO THE TE AROHA DAIRY COMPANY LIMITED, OF TE AROHA, NEW ZEALAND

METHOD OF AND APPARATUS FOR DEODORIZING AND DEHYDRATING FLUIDS

Application filed May 10, 1926, Serial No. 108,185, and in New Zealand May 12, 1925. Renewed November 12, 1931.

This invention relates to improvements in the deodorizing and dehydrating of fluids and more especially to the deodorizing and dehydrating of dairy products, particularly cream. The method and apparatus constituting the subject matter of this invention are further developments of the method and apparatus disclosed in the U. S. patent to H. L. Murray, No. 1,641,349, granted September 6, 1927.

An object of this invention is an apparatus and method for thoroughly deodorizing and dehydrating dairy products at sufficiently low temperatures that the dairy product is nowise damaged.

According to the present invention, the dehydrating and deodorizing is accomplished by washing the dairy product with large quantities of steam vapor during intense boiling of the dairy product under vacuum, thereby maintaining the temperature of the dairy product relatively low. In this way, the odorous principles are eliminated by washing and are conveyed away by steam as a medium of transfer.

Other objects, novel features and advantages of this invention will be apparent from the following specification and accompanying drawings.

Referring to the accompanying drawings which illustrate a constructional embodiment of the invention, Figure 1 is a partially sectioned elevation of a complete apparatus, Figure 2 is a modification of apparatus shown in Figure 1, Figure 3 is a sectional perspective view of the ejector condenser, Figure 4 is a sectional elevation of the float chamber and the froth eradicating valve, Figure 5 is a sectional elevation showing the check valve arrangement on the pump, Figure 6 is a sectional view of the sniffer valve shown in Figure 2, and Figure 7 is a sectional view of the inlet pipe as it passes to the container.

The apparatus as shown in Figure 1 comprises a container 1 substantially cylindrical in shape with substantially hemispherical ends consisting of a top section 2 and a bottom section 3 mounted on four hollow legs 4. The top section 2 acts as a lid to the bottom section 3 an air tight joint between the sec-

tions being formed by recesses 5 and 6 in which are fitted rubber rings 7 which are pressed together tightly. A baffle plate 8 shaped like a reversed saucer and provided with a rim is supported within the container 1 by the rim being tightly held between the rubber rings 7. The baffle plate has one open downwardly projecting preferably cylindrical deflecting portion 10 in its center, and is provided with a circular row of holes 9. The holding together of the top section 2 and bottom section 3 at the rubber rings 7 and also the lifting of the top section 2 for access to the interior of container 1 is effected by four screws 11 operated by a handwheel 12 with bevel pinion 13, and bevel wheel 14 in mesh, the latter being mounted on the screw 11 inside one of the hollow legs 4.

The attaching castings 15 by means of which legs 4 are fastened to container 1 act as bearings for the screws 11 which pass up and through nuts 16 attached to the bottom ends of hollow columns 17 the latter passing through guides 18 attached to the bottom section 3 and being fastened to attaching pieces 19 of the top section 2. Collars 20 are attached to the screws 11 to prevent lateral movement and take downward thrust of the latter, handwheel 12 with bevel wheels 13 and 14 is fitted to one of the legs 4 only, the turning of the handwheel 12 revolving the four screws 11 simultaneously by means of four sprockets 21 attached to the bottom ends of the screws 11 and an endless chain 22 passing over the four sprockets 21 so that turning of the one screw 11 by means of handwheel 12 causes the other three screws 11 to also turn per medium of the endless chain 22. Pipes 23 between legs 4 cover and protect the endless chain 22.

The bottom section 3 is surrounded by a steam jacket 24 and is provided with steam inlet pipe 25 and valve 26 and drain pipe 27. Surrounding the steam jacket 24 there is a heat insulation jacket 28 of any suitable insulating material such as hair felt.

On the top section 2 on the outside, there is fitted a flexible water supply pipe 29 which supplies water through valve 31 for the jet 30 also for the spray pipe 32 through valve 100.

33. The pressure of water at the jet 30 is registered by a gauge 34.

Also fitted to top of top section 2 there is a vacuum breaking cock 35 with cup shaped inlet 36 over which gauze is placed to prevent dirt from being drawn into container 1, and a vacuum gauge 37 and inspection ports 38 and 39 the latter being also a lighting port.

The jet 30 see Figure 3 passes vertically down the center of the container 1 into the ejector or condenser 40 which is a hollow cone in shape open at the top but closed at the bottom by a terminating casting 41 into which is screwed the ejector pipe 42 which passes out at the bottom of container 1, see Figure 1. Centrally situated on the inside of ejector 40 there is a series of cones 43 held in place by four bolts 44 passing from the terminating casting 41 to the top plate 45 the latter having a number of holes 46 so that it will not obstruct passage of vapours to the cones 43.

The cones 43 have their throats 47 gradually increased in size, the top cone having the smallest throat and the others each a little larger than the preceding one. The cones 43 are kept at equal distances by hollow cylindrical distance pieces 48 each distance piece having four ports 49 to allow passage of vapours to the cones 43. This arrangement considerably increases the efficiency of the ejector condenser.

Inside container 1 there are four sweeps 50 fastened to the four sides of a square boss 51 having a seating 52. The boss 51 is fastened to a sleeve 53 which is an extension of a crown wheel 54 the sweepers 50 being rotated by means of the crown wheel 54 and the bevel pinion 55 in mesh therewith attached to shaft 56 at the outer end of which there is a friction clutch 57 with operating handwheel 58, the clutch 57 being supported by a leg 59, side stays 60 to legs 4 and a stay 61 passing between two of the legs 4. A bottom casting 62 is fitted in the center of the bottom of the bottom section 3 which supports the sweeps 50 at the seating 52. This bottom casting has a gland 63 formed in the center to prevent leakage from container 1 past the sleeve 53 which passes through it.

A gland 64 is formed on the under side of the crown wheel 54 to prevent leakage from container 1 past the ejector pipe 42.

A housing 65 is fitted to the under side of the bottom casting 62 which supports the drive shaft 56, the outlet 66 of the ejector pipe 42 and an idler shaft 67 to which is attached a bevel pinion 68 (in gear with crown wheel 54) and a spur wheel 69 the latter driving a spur pinion 70 attached to shaft 71 of centrifugal pump 72 supported by a stay 73 between two of the legs 4.

The suction pipe 74 of the pump 72 is connected to the side of container 1 and is fitted 65 with a thermometer 75, the pump delivery

pipe 76 being fitted with an adjustable check valve 77, see Figure 5, the lift of which is regulated by means of a screw 78.

To the side of bottom section 3 is fitted the liquid inlet mechanism which utilizes the vacuum for getting the liquid into the container 1. This inlet or supply mechanism consists of a float chamber 79 (see Figure 4) at the top of which is the supply pipe 80 with a froth eradicating valve 81 held against its seat by a spring 82, fitted to a removable cover 83 which has a hinged section 84 with a handle 85.

The inlet pipe 86 (see also Figure 7) to the container 1 has a seating 87 over which is placed a slide valve 88 moved backwards and forward by the rise and fall of a float 89 to which is attached lever 90 pivoted on bracket 91.

A removable cap 92 is fitted to a backward extension 93 of inlet pipe 86 so that any liquid in the inlet pipe 86 and float chamber 79 after the operation has been stopped, can be readily removed.

A pipe 94 with cock 95 attached to the bottom of container 1 allows any liquid left therein, after stopping work, to be run off.

A valve 96 on the steam supply pipe 97 allows steam to enter the container 1 through a pipe 98 for sterilizing purposes.

In the modification shown in Figure 2, the construction is substantially similar to that shown in Figure 1, but the container 1 is substantially cylindrical in shape with a parabolic top and hemispherical bottom and a widened steam jacket 24 and is not provided with a separate top and bottom section, the elevating mechanism (reference numbers 11 to 25) being eliminated.

The top of container 1 is provided with a large hole 98a fitted with a cover plate 99 which has three holes in it, two of the holes 100 being provided with inspection ports 38 and 39 (the latter not shown) the other hole 101 having mounted thereto a goose neck pipe 102 which passes from the container 1 to the upper portion of the ejector condenser 40, in this case situated vertically outside of container 1 and supported at its lower end by the terminating casting 41a tapered to fit neatly into a conically bored supporting casting 103 attached to the side of the container 1, this supporting casting 103 having the ejector pipe 42 screwed thereto.

The upper end of the ejector 40 is provided with a cover 104 having a gland 105 through which passes the jet 30 supplied with water by flexible water supply pipe 29 through valve 31 the pressure of water at the jet 30 being registered by the gauge 34.

Fitted to the goose neck pipe 102 there is the vacuum gauge 37 and also a snifter valve 106 (see Figure 6) which comprises a seating 107 with ports 108, the seating, guiding valve 109 attached by a Bowden wire 110 to 130

the end of the lever 111 supported at its knife edge 112 on two fulcrums 113, the lever 111 being screwed 114 for taking two adjustable weights 115.

5 The four sweeps 50 are fastened to square boss 51, which is fastened to a vertical shaft 116 by nut 117 on taper 118 the foot of the shaft 116 having a ball race 119 to take downward thrust, the said shaft 116 having the 10 crown wheel 54 attached thereto.

A short leg 120 under housing 65 gives additional support to the container 1.

To operate the apparatus as disclosed in Figures 1 and 2 assume all valves closed and 15 joints tight.

The container 1 is first of all sterilized by opening valve 96 which admits steam through pipe 98 to the container 1.

The valve 96 is then closed and jet valve 31 20 opened admitting high pressure water to the jet 30 the flow of water through the throats 47 of cones 43 creating vacuum in container 1. The desired vacuum having been obtained as indicated by vacuum gauge 37 the sweeps 25

50 are set in motion by slowly turning the handwheel 58 of friction clutch 57 which is connected by belt to some source of power, the drive being transmitted through shaft 56, bevel pinion 55 crown wheel 54, sleeve 30 53 for Figure 1 and vertical shaft 116 Figure 2, and the square boss 51 to which the sweeps 50 are attached.

The hot liquid to be deodorized or dehydrated is now admitted to the float chamber 79 (see Figure 4) through inlet 80 past froth eradicating valve 81, the float 89 gradually rises moving the slide valve 88 on the seating 87 until the float chamber 79 is open to the inlet pipe 86.

40 The suction caused by the vacuum in container 1 draws the liquid from the float chamber 79 the float 89 rising and falling and preventing the vacuum in container 1 from ever becoming broken by air entering to it 45 through the inlet pipe 86.

Steam is admitted to the steam jacket 24 through pipe 25 by opening valve 26, condensed steam escaping through outlet pipe 27.

The heat of the steam jacket keeps up the 50 temperature of the incoming hot liquid and aids deodorization.

The revolving sweeps 50 and the vacuum in container 1 cause intense ebullition of the liquid which rises and comes in contact with 55 the baffle plate 8 oozing through the holes 9 its further upward course being prevented by the shape of the baffle plate 8 which also serves to deflect the liquid so that it cannot enter the condenser or ejector 40, or goose 60 neck pipe 102 of Figure 2, but falls downwardly. The vacuum draws the hot vapour arising from the liquid through the open top of the ejector 40 in Figure 1 and goose neck pipe 102 of Figure 2, through holes 65 46 in the top plate 45 and through the ports

49 in the distance pieces 48 past the throats 47 of cones 43, through ejector pipe 42 and out of the ejector pipe outlet 66 in condensed form being then preferably carried away to a suitable place by a pipe, the end of which 70 may be immersed in a barrel of water acting as a water seal.

The interior of the container 1 can be inspected during working by means of inspection ports 38 and 39 (the latter not shown in Figure 2), a light being placed over the latter and the glass of the former cleaned whenever desired by opening spray valve 33, a jet of water from spray pipe 32 (not fitted on Figure 2) washing the inner surface of 80 the glass.

In the modification shown in Figure 2, the snifter valve 106, see Figure 6, designed to be finely adjusted and exceedingly delicate in operation, is set to admit air to the container 1 when the vacuum of the latter exceeds the requisite degree for the suitable working of the apparatus; it thus holds the vacuum stable, if the water pressure at the jet 30 varies.

90 While the sweeps 50 are in motion, centrifugal pump 72 is also in motion from the same source of drive, from crown wheel 54 bevel pinion 68 and spur wheel 69 on idler shaft 67 and pinion 70 attached to the pump 95 drive shaft 71 so that when the sweeps 50 are set in motion the pump 72 also rotates.

Liquid in container 1 flows into the suction pipe 74 and falls by gravity to the pump 72, the centrifugal action of which forces 100 the liquid out through delivery pipe 76, the flow being regulated by means of a check valve 77 the lift of which is regulated by adjustment screw 78, see Figure 5. The valve 77 prevents air entering into the container 105 through the delivery pipe 76 and breaking the vacuum.

The deodorizing process is continuous, liquid flowing through steadily, the delivery temperature being determined by the thermometer 75 on pump suction pipe 74.

The odorous principles of the essential oils contained in the cream are eliminated by intense washing of the cream molecules by means of steam obtained from the water content of the cream. The washing operation entrains or dissolves the odorous principles which are conveyed away in steam as a medium of transfer. The steam in the steam jacket supplies heat to the liquid in the container sufficient to insure continued and intense boiling thereof and the vacuum maintained within the container insures constant boiling temperature and the prevention of undue foaming. By means of the sweeps centrifugal force is applied to the cream, thereby producing a revolving wall of cream conforming to the surface of the container. Within the revolving wall of cream are set up horizontal molecular currents from the

hot surface of the container to the inner stratum of the cream. These currents are set up because of the difference in specific gravity between the heated and the cooler molecules. The molecules adjacent the heated surface become surrounded with myriads of vapor bubbles whose presence lowers the specific gravity in that neighborhood with the result that the heat laden molecules become displaced from the heated surface by the cooler and heavier molecules. These in turn likewise become displaced and so a constant procession of molecules is set up. The intense molecular circulation thus brought about greatly assists the transmission of heat from the steam jacket to the cream mass, the result being the very rapid evaporation of part of the water content. The steam vapor thus formed is applied to the individual molecules and serves to entrain, dissolve or absorb the non-volatile odorous substances with which the cream is contaminated. The odorous substances thus removed from the cream are exhausted through the condenser 40.

When it is desired to stop the plant the source of supply is stopped, the float 89, see Figure 4, settles to the bottom of float chamber 79 closing slide valve 88; steam valve 26 is closed when the liquid ceases to flow from delivery 76 and vacuum is broken by opening vacuum breaking cock 35.

The jet 30 is stopped by closing valve 31 and the rotation of pump 72 and sweeps 50 stopped by turning handwheel 58 of the clutch 57.

The liquid left in the bottom of container 1 is run off by opening cock 95.

The top section 2 can then be elevated for cleaning purposes with Figure 1 by turning handwheel 12. This turns one screw 11 through bevel wheel 14 attached thereto and bevel pinion 13 in gear with it the other three screws 11 being turned by the endless chain 22 and sprockets 21, the nuts 16 being forced up the screws 11 lifting the columns 17 guided by guides 18 and the top section 2 attached to the columns 17.

In the modification shown in Figure 2, admittance can be obtained to the container 1 for cleaning purposes by first of all pushing the goose neck 102 away from the cover plate 99 so that it moves radially on the supporting casting 103 the terminating casting 41a turning therein during the operation.

Cover plate 99 is then removed leaving exposed the large hole 98a the moving of the goose neck 102 and the removal of the cover plate 99 being readily done when the container 1 is not under vacuum, the vacuum being ample to keep them in position and air tight when in use.

The vacuum maintained in the container for deodorization is preferably above ten inches of mercury and in the claims the words

"high vacuum" are to be understood as meaning vacuum in excess of ten inches of mercury.

I claim:

1. A vacuum apparatus for deodorizing, dehydrating or pasteurizing liquids comprising a container having a steam jacket, the inner wall of which container is a surface of revolution free from axial projections, means continuously to feed liquid into said container, means for supplying and distributing steam throughout said jacket for heating liquid in the container to and maintaining the same at boiling temperature, a set of sweeps within said container, means to rotate said sweeps, means for positively and continuously withdrawing liquid from said container, means capable of creating and maintaining high vacuum within said container by condensing vapors emanating from said liquid and exhausting fixed gases, and means for preventing increase of vacuum in the container above a predetermined degree thereby maintaining constant the boiling point of the liquid in the container.

2. A vacuum apparatus for deodorizing, dehydrating or pasteurizing liquids comprising a container having a steam jacket, the inner wall of which container is a surface of revolution free from axial projections, means continuously to feed liquid into said container, means for supplying and distributing steam throughout said jacket for heating liquid in the container to and maintaining the same at boiling temperature, a set of sweeps within said container, means to rotate said sweeps, means for positively and continuously withdrawing liquid from said container, means capable of creating and maintaining high vacuum within said container by condensing vapors emanating from said liquid and exhausting fixed gases, an air inlet for said container, and a gravity balanced valve controlling said inlet for preventing increase of vacuum in the container above a predetermined degree, thereby maintaining constant the boiling point of the liquid in the container.

3. A vacuum apparatus for deodorizing, dehydrating or pasteurizing liquids comprising a container having a steam jacket, the inner wall of which container is a surface of revolution free from axial projections, means continuously to feed liquid into said container, means for supplying and distributing steam throughout said jacket for heating liquid in the container to and maintaining the same at boiling temperature, a set of sweeps within said container, means to rotate said sweeps, means for positively and continuously withdrawing liquid from said container, means capable of creating and maintaining high vacuum within said container by condensing vapors emanating from said liquid and exhausting fixed gases, means for preventing increase of vacuum in the container

above a predetermined degree thereby maintaining constant the boiling point of the liquid in the container, and a deflector within said container for returning heated liquid from the upper portion of the container to the central bottom portion thereof.

4. A vacuum apparatus for deodorizing, dehydrating or pasteurizing liquids comprising a container having a steam jacket, the inner wall of which container is a surface of revolution free from axial projections, means continuously to feed liquid into said container, means for supplying and distributing steam throughout said jacket for heating liquid in the container to and maintaining the same at boiling temperature, a set of sweeps within said container, means to rotate said sweeps, means for positively and continuously withdrawing liquid from said container, means capable of creating and maintaining high vacuum within said container by condensing vapors emanating from said liquid and exhausting fixed gases, an air inlet for said container, a gravity balanced valve controlling said inlet for preventing increase of vacuum in the container above a predetermined degree, thereby maintaining constant the boiling point of the liquid in the container, and a deflector within said container for returning heated liquid from the upper portion of the container to the central bottom portion thereof.

5. The method of deodorizing liquids by evaporating volatile essences and entraining non-volatile odorous substances, said method consisting in continuously introducing liquid into a container, supplying heat to said container to heat the liquid within the container to and maintain the same at boiling temperature, applying centrifugal force to said liquid to produce a revolving wall of liquid and effect horizontal radial molecular circulation within said wall of liquid thereby continuously expelling vapors and fixed gases from within the liquid, continuously condensing said vapors and exhausting fixed gases thereby maintaining high vacuum in said container, continuously withdrawing liquid from said container and preventing increase in vacuum above a predetermined degree thereby controlling the boiling point of the liquid.

In testimony whereof I affix my signature.
HENRY LAMONT MURRAY.
